CONNECTER FOR ELECTRIC CIRCUITS

Carl H. Culver and Charles G. Lee, Detroit, Mich.,
assignors to Culver Manufacturing Company,
Detroit, Mich., a corporation of Michigan

Application September 4, 1934, Serial No. 742,676

5 Claims. (Cl. 173—328)

The invention relates to connectors for electric circuits and has for its primary object the obtaining of a construction that may be quickly attached and securely held against accidental displacement. It is a further object to obtain a construction formed of stampings adapted for quick assembly and to maintain good electrical contact in engaged position. With these objects in view the invention consists in the construction 5 as hereinafter set forth.

In the drawing:

Fig. 1 is a perspective view of the cooperating members of the connector in position ready for engagement;

Fig. 2 is a central longitudinal section through the connector in coupled position;

Figs. 3, 4 and 5 are perspective views of the several elements of the assembly.

For certain electrical installations, such for 20 instance as the equipment on motor vehicles, it is highly desirable to provide electrical connectors which can be quickly engaged and securely fastened. This is particularly desirable where motor cars are assembled on a traveling carrier 25 and where it is necessary for each workman to complete his task in a relatively short interval of time. Thus with the type of connectors which are fastened by screws, it has been found difficult for a single workman to make all of the different electrical connections during the time 30 available. On the other hand, connectors which are not fastened with screws but are held in place by friction, frequently become accidentally detached or loosened so as to interrupt the electrical 35 circuits.

With this improved construction connection may be quickly made by sliding one member into engagement with its cooperating member, and provision is also made for automatically locking 40 the parts in engaged position and for pressing the cooperating contacts in close contact with each other.

The improved construction consists essentially of a post stationary contact member, a cooperating 45 contact member secured to the flexible electrical conductor having a telescopic engagement with said post and a latch locking member for holding said contact members from displacement when once fully engaged.

For cheapness in manufacture all of these 50 parts are preferably formed of metal stampings and the construction is also such that a single rivet is sufficient to secure two of the members to each other and to the insulator support therefor, 55 while the third member is readily attachable to

the flexible conductor. In detail, A is the post contact member which is in the form of an angle bar having the base portion A' and the projecting contact portion A². The base portion has an aperture A³ for receiving a rivet and is further provided with a projecting tongue A⁴ for engagement with a recess in the insulator support so as to prevent turning on the rivet. B is a spring latch lock member which is also of angle form having a base portion B' with a rivet aperture B² and a bifurcated extension B³ for engagement with the tongue A⁴. The outwardly projecting portion B⁴ is formed with a locking shoulder B⁵ and a flaring projection B⁶. The members A and B are assembled by registering 10 the apertures A³ and B² and a single rivet C then serves to secure these members to each other and to an insulator support D. As before stated, the tongue A⁴ projects into a recess or aperture D' in the insulator support so as to prevent turning 15 on the rivet into engagement between the bifurcated portion B³ and said tongue also prevents turning of the member B.

E is the contact member which is engaged with the flexible conductor. This is formed with a 20 flat face E' for engagement with the post A and angle flanges E² on opposite sides thereof for embracing the post to hold the portion E' in contact therewith while permitting of telescopic engagement. The portion E' has also a struck-out portion E³ which forms a locking shoulder for engagement with the spring latch. Beyond these portions is a shank portion E⁴ initially bent into U cross sectional form with separate prongs E⁵ and E⁶ for respectively closing over the bared 25 wire and the insulated portion of the flexible conductor F. Thus to attach the member E to the flexible conductor F it is only necessary to bare the end portion of the wire and then place it in the U-shaped shank E⁴, turning down the 30 prongs E⁵ and E⁶ respectively on the bare wire and the insulator covering. As soldered electrical connections are usually required, this may be 35 quickly accomplished by dipping the member E into a solder pot and to a sufficient depth to cover the prongs E⁵.

With the construction as described, the flexible conductor with the contact member E attached thereto can be quickly telescopically engaged with the post contact A. As soon as the 40 struck out portion E³ is pressed past the latch shoulder B⁵, the latter will engage therewith and will not only prevent disengagement but will also serve to press the surface E' in firm contact with the post. This insures good electrical 45 contact with the post. This insures good electrical 50 contact with the post. This insures good electrical 55 contact with the post.

cal connection. The construction is also one which can not be loosened by jar or vibration, or even limited mechanical stresses on the flexible conductors. This is for the reason that the 5 post A is comparatively rigid and can not be laterally displaced by any stress to which it is normally subjected. The member E is also held from lateral displacement by its telescopic engagement with the post A and by reason of the 10 hooked or angle flanges E². Thus no stress can be placed by either of these members upon the resilient and flexible member B and consequently when the latch shoulder B⁵ has once engaged with the projection E³, it is impossible to 15 disengage the members E and A by a pull upon the conductor F. When, however, it is desired to detach the connector by inserting a screw driver or other like tool between the post A and the member B, the latter may be sprung outward 20 so as to disengage the shoulder B⁵ from the projection E³ whereupon the connector may be readily pulled off from the post A.

What we claim as our invention is:

1. The combination of a pair of angle members, one being substantially rigid and the other flexible and resilient, an insulator support, a fastener passing through registering apertures in the base portion of said angle members and said insulator support to secure the same to each 25 other, a tongue projecting from said rigid angle member entering a recess in said insulator support, a bifurcated portion on said resilient member for embracing said tongue, a flexible insulated conductor, a terminal contact for said conductor 30 having a portion for clinching engagement with the insulating cover therefor and a portion for clinching engagement with the bared wire, said contact being adapted for telescopic engagement with the projecting portion of said rigid angle 35 member and having a struck out portion for forming a locking shoulder, and a hooked shoulder on the projecting portion of said flexible angle member for engaging said struck out portion when said terminal member is telescopic- 40 ly engaged with said post to hold the same from 45 disengagement.

2. The combination of a pair of angle members, one being substantially rigid and the other flexible and resilient, an insulator support, a 50 securing rivet passing through registering apertures in the base portions of said angle members, and said insulator support to hold the same to each other, a tongue projecting from said rigid angle member entering a recess in said insulator support, a bifurcated portion on said flexible angle member for embracing said tongue whereby 55 both of said angle members are held from turning on said rivet, a flexible insulated conductor, a terminal contact for said flexible conductor 60 having a shank portion provided with a plurality of projecting prongs, certain of said prongs adapted for clinching engagement with the insulator cover of said flexible conductor, and one or more of said prongs being adapted for clinching engagement with the bared end portion of 65

said conductor, said terminal contact being provided with angle flanges on its opposite sides for embracing and telescopically engaging the projecting portion of said rigid angle member and being further provided with a struck-out shoulder portion, and a hooked shoulder on the projecting portion of said flexible angle member adapted for latching engagement with said struck-out shoulder to retain said terminal contact and said post from disengagement. 10

3. The combination of a pair of angle members, one being substantially rigid and the other flexible and resilient, an insulator support, a fastener passing through registering apertures in the base portions of said angle members and said insulator support to secure the same to each other with the flexible member clamped between the rigid member and support, a tongue projecting from said rigid angle member passing through an aperture in said resilient member and entering a recess in said insulator support, a contact member secured to and forming a terminal for a flexible conductor, said contact member being fashioned to embrace and telescopically engage the projecting portion of said rigid angle member and being also provided with a struck-out shoulder, and a hook on the projecting portion of said flexible angle member adapted for latching engagement with said struck-out shoulder to retain said terminal contact and said post from 20 disengagement. 25

4. The combination of a pair of angle members, one being substantially rigid and the other resiliently flexible, an insulator support, a rivet passing through registering apertures in the base 30 portions of said angle members and insulator support to secure the same to each other, a tongue projecting from the base portion of said rigid angle member and through an aperture in the base of said flexible angle member into a recess 35 in said insulator support to hold said members from turning, and a contact member forming the terminal of a flexible conductor telescopically 40 engaging said rigid angle member and locked in engagement by said resilient member. 45

5. The combination of a pair of angle members, one being substantially rigid and the other resiliently flexible, an insulator support, a rivet passing through registering apertures in the base portions of said angle members and insulator support to secure the same to each other, a tongue projecting from the base portion of 50 said rigid angle member and through an aperture in the base of said flexible angle member into said recess in said insulator support to hold 55 said members from turning, a contact member forming the terminal of a flexible conductor telescopically engaging said rigid angle member, and cooperating detents on said flexible angle member and contact member permitting a latch engagement thereof and preventing accidental disengagement. 60
